PRINTING APPARATUS

Henry Van Riper Scheel, Passaic, N. J.

Application September 13, 1935, Serial No. 40,399

14 Claims. (Cl. 101—56)

This invention relates to methods and means of marking sheet material and especially to methods and means of printing the surface of sheet material. The invention particularly relates to methods and means of printing, by means of plates or similar printing device, sheets of standard or predetermined size and shape with the printing to be applied thereto in a predetermined relation to forms, diagrams or other printing previously applied to the sheet.

Many devices are now in use for printing from a prepared printing element or plate, containing the form or design to be printed impressed, molded or otherwise formed in the element or plate and so arranged that when a sheet of material of predetermined shape and size is placed in a predetermined relation to said printing element or plate an impression or imprint of said plate may be made upon the face of the sheet. Such devices have been so constructed and arranged that, when preprinted with a desired form, such as a bill or voucher form or a sales slip or other document bearing an arrangement of lines, printing and similar marks, said sheet may be so placed in the machine or device that with a single stroke or action of the machine, either automatically or at the will of the operator, an impression or imprint from the plate may be made upon the surface of the sheet in a definite and predetermined relation to said form printed thereon. For example, a bill or a payment voucher prepared by such a machine as a tabulating billing machine, or when prepared by means of a typewriter or other printing device, may subsequently require the imprint of the name of the customer or of the vendor of the goods as the case may be. This imprint of the customer's or vendor's name may be accompanied by the address, by identification numbers or other symbols, depending upon the purpose of the bill, voucher or other document.

In order to facilitate the work of preparing such documents, heretofore there have been in use printing elements or plates of permanent character in which are formed as by molding or die pressing, the name of the customer or vendor or other name of person or corporation, together with such other identifying and ancillary data and information as is suitable for the purpose in hand. In many cases such plates have been arranged in devices with mechanism for applying ink or other printing material to the face of the letters or other printing surface, an impress or imprint of the inked surfaces of the plate upon a face of the sheet then being made. In a device shown and described in the United States Letters

Patent No. 1,801,592 instead of the ink or printing material being first applied to the printing surface of the plate the parts are so arranged with respect to the sheet to be printed that the printing surface of the plate is adjacent one face of the sheet and the means for applying the ink or other printing material is adjacent the other face of the sheet, pressure being so applied as to cause the printing surfaces of the plate to contact the sheet and by pressure through the sheet to cause the printing material to be applied to the opposite face of the sheet in areas corresponding to the printing surfaces of the plate.

Apparatus has also been proposed heretofore for feeding a continuous sheet lengthwise thereof, which sheet has been prepared by printing or other process with marks or imprint occupying successive predetermined areas and in predetermined relation to each other in the length of the sheet, to provide the documentary forms referred to above. These devices have been provided with mechanisms for feeding such a sheet intermittently, that is, from a position in which one predetermined area of the sheet may be printed to a position in which an adjacent similar area is in position to be printed, thereupon stopping the sheet and holding the sheet in said second position until the printing or other marking is applied thereto.

The present invention is concerned with methods of which the methods carried out by means of apparatus functioning in the manner described in said Patent No. 1,801,592 and by means of apparatus for effecting intermittent motion of the sheet as just referred to are typical. Especially when utilizing printing elements or plates which have predetermined forms thereon for the printing of predetermined and definite information, and particularly when such information is to be used repeatedly for printing upon documents or forms such as bills, vouchers, etc., it becomes necessary to be able readily to select the desired printing element or plate containing the required information. In many cases with the apparatus as heretofore used it has been necessary to select a plurality of said printing elements or plates, and to arrange them in a predetermined order so that they might be fed to the device for printing upon the sheet. The present invention has for one of its purposes the elimination of the necessity of arranging the selected plates in a predetermined order for use in the printing device.

By means of the apparatus of the present invention operated in the manner hereafter to be

described it becomes necessary only to select the desired printing element or plate in the order as determined and indicated by the order of delivery of the form, bill, voucher or other document 5 through the feeding machine. As this feeding is intermittent and as such a form, bill, voucher or other document may contain, by the entry thereon of the individual items of sale, purchase or other information, an indication which will identify 10 it with the name of the customer, vendor or other party to which the document refers, the printing element or plate may be at once selected from its file and may be inserted in the machine for printing upon the particular form or document before 15 movement again is given to the continuous sheet to move the succeeding area occupied by the succeeding form or document into the printing position.

In order to carry out this purpose of the invention, and particularly in order to maintain the 20 advantage of feeding a continuous sheet which carries, upon succeeding areas thereof, a series of forms or documents upon which the information contained in the successive printing elements 25 or plates is to be printed, the invention so arranges the apparatus and the various devices that the printing element may be moved into and out of its printing position and into and out of a position in which it is accessible for removal and replacement by another similar printing element, 30 this movement preferably being effected while the sheet is at rest. During this period of rest between the movements of the sheet to bring the successive areas thereof into printing position, 35 not only may the succeeding document be identified in order properly to select the corresponding printing element or plate but during this period the printing element previously used may be removed from the device and immediately replaced 40 in its file, the printing element required for the next document being immediately selected and placed in the printing device. Upon movement of the printing device into printing position the next form or document then may be printed.

In order, however, to make accessible the printing element so that it conveniently may be removed from the device it becomes necessary so to arrange the apparatus that the printing element 45 may be moved into a position clear of the sheet, it being not possible or at least being inconvenient 50 to move the sheet clear of the printing device because the sheet is continuous and has printed on it in the successive areas lengthwise thereof the forms or documents identified or to be identified 55 with a customer or vendor's name or other name and ancillary information carried by the printing element. It is preferable to keep the continuous sheet in its feeding position so that the operator can readily see it and the information or record thereon and can control its feeding 60 movement.

While in printing devices in general use heretofore the printing element has been moved into contact with the sheet, and after the impress or 65 imprint has been made has been moved out of contact with the sheet, I propose by the arrangement of my invention to move the printing element or plate in a direction which is like-extending 70 with one of the surface dimensions of the sheet and preferably transversely of the direction of the motion of the continuous sheet. By such a movement, particularly when the movement is transversely of the direction of motion of the sheet, the printing element may be moved into a position clear of the sheet, which makes it

accessible for replacement by another printing element without disturbing or requiring motion of the mechanism for feeding the sheet. Moreover, when utilizing the printing element of the type described in said Patent No. 1,801,592, by 5 means of which the printing surfaces or characters upon the printing element or plate may be in such form as to be read directly, that is, they are in the "non-reversed order" as in ordinary printing elements or plates, this movement 10 of the printing element into a position clear of the sheet may be so effected as to maintain said element in position to be directly read when clear 15 of the sheet. In many printing devices the movement of the printing element out of contact 18 with the sheet, whether or not the printing surfaces or characters may be directly read, is effected in such a way that the element cannot be seen in the position clear of the sheet. This is true 20 of many rotary printing devices. By utilizing an arrangement of the printing element or plate with respect to the sheet and an arrangement of the mechanism and means for applying the ink or printing material to the sheet in the manner as disclosed in said Patent No. 1,801,592, I maintain 25 the advantage of avoiding the application of the ink or printing material to the printing surfaces of the printing element and of conveniently changing the printing elements or plates without soiling the hands of the operator, the element removed being immediately filed and the new element being immediately found and inserted in the manner referred to above.

The movement of the printing element in a direction like-extending with the surface dimension of the sheet and preferably transversely of its motion may be accomplished by means which in a simple embodiment are reciprocable in a plane substantially parallel to the face of the sheet into and out of the printing position and into and out of a position in which the printing element clear of the sheet may be removed and replaced by another printing element. Within the scope of the invention however the movement of the printing element may have a component in said direction like-extending with the surface dimension of the sheet and also a component transversely of the surface of the sheet to move said element into accessible position clear of the sheet.

My invention also includes means for accomplishing the intermittent motion of the sheet under the control of the operator while securing the motion thereof through the desired or predetermined distance from the printing position upon one form or document to the printing position upon another form or document. Moreover, the apparatus of the invention includes means for effecting such movement between two printing positions upon the same form or document, that is, upon a single area of the sheet while also being effective to move the sheet to the printing position of the succeeding form or document. This movement and these movements may be effected by the means provided by the invention so as to effect the subsidiary movement within a given area of a form or document, that is, from one printing position within said area to another printing position within said area. If desired in the succeeding area only a single impress may be taken while in the second succeeding area the sheet may be stopped for two or more such imprints or imprints. Other combinations may be made as desired, as will be more clearly under-

stood from the description to follow in connection with the drawings.

The invention provides means for producing a positive movement of the sheet through predetermined distances between the positions of the succeeding areas thereof for imprinting. The invention also provides for cooperation of the means for effecting the intermittent motion and of the means for effecting this motion in a positive predetermined manner with means for effecting the movement of the printing element or plate in the direction like-extending with the surface of the sheet.

The invention in certain phases thereof provides for automatic movement of the printing element or plate from the printing position to the position clear of the sheet. This phase of the invention further includes means for automatically effecting release of the plate or of the plate supporting means upon actuation of the means for producing movement of the sheet. The invention further contemplates, upon restoration of the means for supporting the plate or the printing element to the printing position, engagement of said plate supporting means with said holding means, said engaging means being biased to engage the plate or its supporting means and to hold it in the printing position. Likewise, the invention contemplates release of the plate or its supporting means upon actuation of the means for holding the sheet in the printing position when said means is actuated to release the sheet to permit motion thereof.

The invention now will be more clearly understood from the following description of the drawings in which

Figure 1 shows a plan view of apparatus embodying the invention;

Figure 2 shows in elevation apparatus embodying the invention;

Figure 3 shows in enlarged detail the arrangement of a printing device according to the invention;

Figure 4 is a section on line 4—4 of Figure 2;

Figure 5 shows a modified arrangement of the apparatus of the invention;

Figure 6 shows a section on line 6—6 of Figure 5; and

Figures 7 and 8 show details of a member of the apparatus of the invention.

In Figure 1 a table or other suitable support is shown at 1. Arranged in suitable relation to said table is a receptacle 3 in which may be placed the sheet material 5 folded in the manner of a fan so that the sheet 5 may be fed therefrom as a continuous sheet of considerable length. If desired, however, for the receptacle 3 containing the folded sheet 5, a roll revolving upon an axis and having wound thereon the continuous sheet 5 may be substituted. Supported by suitable bearings 7 fastened to the underside of the table 1 is mounted the roll 9, in contact with the circumferential surface of which the sheet 5 passes and is carried forward to the roll 11 similarly supported by bearings 8 at the front side of the table 1. The rolls 9 and 11 are so mounted with respect to the surface of the table 1 that their circumferential surface is somewhat above the surface of said table. Thus the sheet 5 may be carried forward from the box 3 over the rolls 9 and 11 and may be delivered to the box 13 at the front side of the table into which it may be delivered in the folded arrangement or in any desired manner. If preferred, in place of the box 13 by means of a take-up roll, the sheet 5 may

be wound at the delivery side of the apparatus.

The roll 11 may be provided with pins 12 when, as in some cases, the sheet 5 is provided with perforations so as to secure a positive movement of said sheet 5 under the action of the roll 11 when said roll is positively rotated. If desired, the roll 9 also may be provided with pins as is the roll 11 to maintain alignment of the sheet. In some cases, however, this provision is unnecessary, the alignment of the sheet being sufficiently well insured by the feeding of the sheet from the box 3 or other supply device as it is drawn forward by the pins 12 on the roll 11.

As may be seen from Figure 2, upon the ends of the shaft 14 carrying the roll 11 are mounted pinions 16 and 17. The pinion 16 meshes with the gear 18 keyed upon the shaft 20 supported in a bearing bracket 21 fastened to the under side of the table 1. Upon the opposite end of the shaft 20 is fastened one member 22 of a clutch, of which the other clutch member is 23. By means of a suitable spring 25 the clutch member 23 is biased to a position of disengagement from the clutch member 22. Said clutch member 23 is provided with a hub 27 internally grooved to fit a splined shaft 28 so as to be positively driven upon rotation of said shaft 28.

At 30 is shown the casing of a reduction gear of any suitable type, the shaft 28 extending through one wall of said casing and the shaft 32 extending through the opposite wall of said casing 30. Between the shaft 32 and the shaft 28 gearing is provided to effect a reduction of the speed of the shaft 28 with respect to shaft 32. Fastened upon the shaft 32 is a pulley 33 over which passes a belt 34, said belt also passing over a pulley 35 upon the shaft of a motor 36.

From the description so far given of the apparatus shown in Figure 2 it will be apparent that the motor 36 may drive the clutch member 23 with a positive continuous rotation and in a speed relation to that of the motor 36 determined by the ratio of the pulleys 33 and 34 and the gear ratio of the reduction gear 30. Upon engagement of the clutch member 23 with the clutch member 22 rotation may be given to the roll 11 through the gears 18 and 16. The ratio of the gears 16 and 18 may be such as to provide for mounting of the parts below the table 1 and the over-all ratio between the speed of the motor 36 and the speed of the roll 11 is preferably so arranged that with a constant rotation of the motor 36 the roll 11 may be moved at a speed suitable for the particular work in hand in consideration of the character of the sheet and of the length of the form areas to be printed or the space between the successive printing positions upon the sheet. If, for example, in a practical case, the speed of the motor 36 is 1500 R. P. M. the speed reduction effected for the roll 11 may be such as to cause said roll to rotate at about 50 R. P. M.

If the diameter of the roll is, for example, about $3\frac{1}{3}$ " then the circumference of the roll being about 10", the speed of the sheet would be about 500 inches per minute. It will be understood, however, that the clutch member 23 may be so operated as to engage the clutch member 22 only for such a short time that the roll 11 will be given only a fraction of a revolution or such number of revolutions as will move the sheet forward the desired or predetermined length. This predetermined length, as has been explained above, may be the length of the form or document being printed or may be the distance between two printing positions on the same form.

As shown in Figure 2 the pinion 17 engages the gear 40 which is mounted upon the shaft 39 which extends from one side of the reduction gear, of which the casing is shown in Figure 2 at 42. From the other side of said casing 42 extends the other shaft 41 of the reduction gear. Upon said shaft 41 so extending is fastened a cam 44, of which one form may be seen in Figure 4. For reasons which will be clear from further description to follow, the ratio of the revolutions of the cam 44 with respect to the revolutions of the roll 11 is such that the cam 44, in the particular embodiment shown in Figure 4, rotates one revolution for a movement of the sheet 5 equal to one form length or between equidistant printing positions lengthwise of the sheet 5. If, as in the example given above, the roll 11 is $3\frac{1}{3}$ " diameter, equivalent approximately to 10" circumference, and if the length of the form to be printed is also 10", and if also one imprint is to be made upon the sheet 5 for each form length, then, taking into consideration the ratio of the gears 17 and 40, the gear ratio provided by the reduction gear 42 must be such as to secure one revolution of the cam 44 for one revolution of the roll 11. If, however, the diameter of the roll 11 were about $\frac{3}{4}$ " giving a circumference of the roll 11 of 2.36" requiring somewhat more than four revolutions of said roll 11 for a form length of about 10", then approximately, with the form of cam 44 illustrated in Figure 4 having one recess 46 in the circumference thereof, the ratio between the revolutions of the cam 44 and the roll 11 should be approximately as 1 to 4.

Pivoted upon a suitable bracket 51, as shown in Figure 2, is a bell crank lever 50 having an arm 52 extending to engage the clutch member 23. Said engagement is effected in the well known manner by a fork 53 formed at the upper end of the arm 52. Fastened in the branches of said fork are studs 54 which operably fit in the groove 56 of the portion 58 of the clutch member 23. Movement of the arm 52 toward the right about the shaft 55 fastened in the bracket 51 causes movement of the clutch member 23 into clutching engagement with the clutch member 22 to cause rotation thereof and of the roll 11, as described above.

The bell crank lever 50 has its arm 60 extending generally horizontally under the apparatus and carries adjacent its outer end a cam ball 62 supported between lugs 63 to rotate upon a stud 64. The cam ball 62 is so formed as to bear upon the circumference 43 of the cam 44 and upon the curved surface 45 of the depression or notch in said cam 44. Under the action of the spring 25 acting to separate the clutch members 22 and 23 or, if necessary, by the aid of an auxiliary spring 65 fastened to a pin 67 at the extremity of the arm 60 of the bell crank 50, said bell crank is biased to move so that the arm 52 holds the clutch member 23 out of engagement with the clutch member 22. The extremity of the arm 60 of the bell crank 50 may be guided in a suitable bracket 68 fastened upon the under side of the table 1. The spring 65 may be connected to a pin 69 fastened in said bracket 68.

As shown in Figures 2 and 4, fastened to the arm 60 by means of a connecting pin 72 is a rod 73 connected at its lower end to a treadle 75. A pin 76 passes through a slot 77 in the web 78 and provides for the angular motion of the treadle 75. The treadle 75 is pivoted upon a pin 79 in a suitable bracket 80 fastened upon the floor.

From the above description and from Figures 2 and 4 it now will be clear that upon pressing down upon the treadle 75 the cam ball 62 is moved outwardly from the notch 46 and the clutch member 23 is moved into engagement with the clutch member 22. Thereupon, movement is given to the roll 11 to draw forward the sheet 5. When said movement is thus given to the roll 11 movement is also given to the cam 44. The treadle conveniently may be held down by the operator until the cam has rotated to bring the circumferential portion 43 thereof into contact with the cam ball 62. Thereafter the cam will hold the arm 60 of the bell crank depressed, and correspondingly the clutch members 23 and 22 will remain in driving engagement, throughout that portion of the rotation of the cam 44 which is of uniform circular outline, that is, while the cam ball 62 is rolling upon the portion 43 of said cam 44.

When the cam ball 62 has reached the point 47, under the action of the springs 25 and 65 the cam ball will be forced into the notch 46 of the cam 44. Correspondingly, the clutch members 23 and 22 will be disengaged from driving contact with each other and the roll 11 may cease to rotate and the sheet 5 may be stopped. Likewise, the cam 44 is stopped and the cam ball remains in the notch 46 as shown in Figure 4, thus holding the cam against rotation and holding the sheet 30 in a predetermined position with respect to the previous similar position of the cam 44 prior to drawing the sheet forward in the manner just described. It will thus be apparent that by means of the cam 44 and the notch 46 thereof acting 35 with the mechanism for starting and stopping the rotation of the roll 11, an exact and predetermined movement of the sheet 5 may be obtained between two printing positions, that is, between two form lengths upon the sheet 5.

If it is desired to move the sheet into more than one printing position per form length then a cam of the form as shown in Figure 7 or Figure 8 may be used. When a cam of the outline shown in Figure 7 is substituted for the cam 44 of Figure 4 the sheet will be stopped at two points in the revolution of the cam, that is, at two points in a form length. These points with a cam of the outline shown in Figure 7 will be spaced approximately equidistant lengthwise of the sheet 5. If a cam of the form shown in Figure 8 is utilized, in which the notches instead of being opposite each other as in Figure 7 are in a different angular relation, the sheet may be stopped at points spaced apart lengthwise of the sheet determined by the angular displacement of one notch with respect to the other. It will be understood in the above description that these cams are intended to replace cam 44 which, as mentioned above, in the particular embodiment of the invention being described rotates one revolution per form length, which may be one revolution in four revolutions of the roll 11. If a different length of sheet or a different form length is to be printed, modifications also may be obtained by changing the size of the roll 11 or by changing the gear ratio of the reduction gear 42. By these variations it will be possible to secure one, two or more printing positions per form length for any desired length of form.

Mounted above the table 1 upon a stud 85 passing through the table and into a bearing 87 upon the under side of the table is a support 89. Said support 89 may be fastened to the stud 85 by a pin 90 as may be seen in Figure 3. The stud 85

is fitted to rotate in the bearing 87. The under side of the support 89 is provided with a boss 92 bearing upon the upper face of the table 1. The bearing 87 is fastened by suitable fasteners 88 against rotation. In the bore 94 of a hub 96 extending laterally of the stud 85 is positioned a spring 97 held in place by a screw 98. The spring holds a ball 99 against the stud 85. The stud 85 is provided with recesses 100 spaced about the circumference of the stud. The support 89 thus may be swung upon the axis of the stud 85 into different positions and the recess 100 may be so positioned upon the stud with respect to the support 89 as to hold said support in desired positions, such as may be seen in Figure 1, when the ball 99 is in register with said recesses. This construction provides, however, for easy release of the support 89 so that it may readily be moved from one position to the other; that is, for example, from the dotted position in Figure 1 to the full line position, and then may be held in the new position.

The support 89 is formed with a slot 102 between an upper extension 104 and a lower arm 106. The recess 102, as may be seen from Figure 3, provides space through which the sheet 5 may pass in its movement with respect to a printing device 107. Said printing device may be of any suitable character. A particular form of the device suitable for the purposes of the present invention will be described hereafter.

The device 107 may be carried by the upper extension 104 upon a bearing 108, pivoting upon a pin 109 in this bearing. The device 107, as may be seen from Figure 3, thus may be tilted from the position in full lines; in which it is arranged adjacent the sheet 5 for effecting the printing, to the position exposing the upper surface of the sheet when the support 89 is in the position shown in dotted outline in Figure 3. The position for printing also is shown in Figure 1. When the device 107 is in the tilted position it may rest against a stop 111 carried by the extension 104.

The particular printing device shown in Figures 1 and 3 of the drawings is of the type in which a printing element 110 is positioned below the sheet 5 with its printing surfaces 113 adjacent the lower face of the sheet 5. The printing element 110 is suitably fastened in the arm 106, which is of such rigidity as to support the printing element 110 to receive the pressure applied upon the upper face of the sheet 5 by the mechanism of the printing device 107, the printing being effected by pressure through the sheet 5 upon the printing surfaces 113. Thus the surfaces 113 do not become coated with ink or marking material and when the printing device 107 is tilted into the dotted position of Figure 3 movement of the device 107 as a whole may be effected relative to the sheet without danger of smearing or otherwise marring the sheet.

It will now be understood that the support 89, together with the printing device 107 and the printing element 110, may be rotated upon the axis of the stud 85 into the position shown in full lines in Figure 1, clear of the sheet, the device 107 being tilted to expose the printing element 110. The printing element 110, therefore, is accessible in a position clear of the sheet so that it may be removed from the arm 106, a new printing element may be inserted and the support 89 then may be swung upon the axis of the stud 85 into the dotted position shown in Figure 1. In these movements the ball 99, dropping into the respective recesses 100, will hold the support 89 and,

therefore, the printing device 107 and the plate 110 respectively in the position clear of the sheet and in the printing position adjacent the surfaces of the sheet.

It will be understood that the printing element 110, arranged in the manner described, may be of that type in which the printing surfaces or characters thereon may be in the "non-reversed order". Thus the characters readily may be read upon lifting the printing device 107. The printing element 110, therefore, may be removed from its support in the arm 106 and immediately filed in a file placed convenient to the table. Likewise, from this file readily may be selected a printing element with which to print the succeeding form upon the sheet. This second printing element may be inserted at once in the arm 106 of the support 89 while the printing device 107 is lifted and the support 89 is in the full line position shown in Figure 1. The support 89 then may be swung into the dotted position in Figure 1, the arm 106 carrying the printing element passing below the sheet 5. The printing device 107 then may be tilted down into the full line position shown in Figure 3 and the handle 112 thereof thereafter may be depressed to effect the application of the ink or marking material in the manner referred to above. Immediately upon completion of the inking motion, that is, by allowing return of the handle 112 upward, the printing device 107 may be tilted and the support 89 swung out into the position clear of the sheet where the next change of the printing elements or plates may be effected. As the printing elements 110 are without ink applied to the printing surfaces thereof they may be handled without danger of smudging the sheet, the operator's hands may be kept clean and the files of these elements also may be kept clean and orderly.

While these features of the printing device itself heretofore have been known, the invention makes possible the use of such a device and affords the advantages thereof when used in connection with a continuous sheet, or a succession of sheets fed one after the other through the printing position, upon which sheet successive imprints are to be made lengthwise thereof and particularly upon such a sheet or succession of sheets which constitute substantially a series of forms or form areas in which the imprint is to be made in definite relation to the form areas or to a form of particular design printed thereon. It will be recognized from the above description that the movement of the printing element 110 is in a direction generally like-extending with a surface dimension of the sheet 5. In the particular embodiment this movement is in a plane parallel to the faces of the sheet 5. This movement makes possible ready access to the printing element 110 when clear of the sheet without complicated mechanism to bring the printing element into a position clear of the sheet, as well as into a position in which the operator may at once see the element when clear of the sheet and have access thereto from the position of operating the machine or of feeding the sheet forward.

In Figure 5 is shown a form of the printing device and the inking mechanism thereof of the type referred to in said Patent No. 1,801,592, modified to suit the purposes of the present invention. The handle 112 is pivoted upon a pin 114 carried by a bracket 116 at the upper portion of the device 107. Passing through a hub 118 is a plunger 120 connected by means of a pin 121.

to the handle 112. Upon the lower end of the plunger 120 is fastened a cam member 122. Suitably pivoted upon a pin 124 is an arm 126 carrying a roller 128 arranged to rotate upon the pin 129. Movement of the handle 112 downward causes the cam surface 123 to bear against the circumference of the roller 128 and to cause the arm 126 to move toward the right in Figure 5. The arm 126, by means of spring 130 and bracket 132, is biased toward the left in Figure 5. Fastened to the casing of the printing device 107 is a guide piece 134 provided with a slot 136. A roll 138 is provided with a rolling surface 140 of such diameter as to easily fit in the slot 136. The diameter of the roll 138 is such in consideration of its mounting in the slot 136 that the circumference thereof bears upon the upper face of the sheet 5 to cause said sheet to press upon the printing surfaces 113 under the weight of the roll 138. A pin-like extension 142 of the roll 138 is engaged by a slot 144 in the lower end of the arm 126. As the handle 112 is depressed and the arm 126 moves toward the right against the bias of the spring 130 under the action of the cam 123, the roll 138 is caused to move horizontally in the slot 136 to the right hand end thereof. When the handle is allowed to return upward under the action of the spring 130 the roll 138 is then returned to the left in the slot 136 to the position shown in Figure 5. The proportions of the parts are such with respect to the extent of the printing element 110 that the roll 138 contacts with all the printing surfaces 113 of said element in its motion from one end of the slot 136 to the other. If, now, a ribbon 146, passing between reels 147 is held in position by guide plates 148 so as to have a portion of its extent closely adjacent to the upper face of the sheet 5 and in such position with respect to the slot 136 that the roller bears upon the ribbon and causes the ribbon to contact with the sheet 5, ink carried by the ribbon will be transferred to the sheet and applied thereto only upon the portions thereof which are pressed against the printing surfaces 113 of the plate or printing element 110.

In the embodiment illustrated in Figure 5 the handle 112 is provided with an extension 150 formed at its extremity with a hooked portion 151. This hooked portion 151 engages a pin 153 upon the upper end of a slide 155 arranged to slide upwardly and downwardly in a slide bracket 157. The hooked portion 151 of the extension 150 is so formed that the printing device 107 may be tilted in the manner described in connection with Figures 1 and 3, the hook thus clearing the pin 153, the slide 155 being held against downward movement by a pin or lug 158 upon which the slide 155 may rest. When the device 107 is tilted down into position, the hook 151 again may engage the pin 153.

Pivoted upon a pin 160 carried by an extension 162 of the slide bracket 157 is a pawl 164. The pawl 164 is so formed and arranged as to be contacted by a pin or lug 166 carried by the slide 155. The pawl 164 also is provided with a toe 168 which contacts the end of a lever 170 pivoted upon a pin 171 carried by a bracket 172 extending upwardly from the extension 104 of the support 89. Said lever 170 is biased by means of spring 173 fastened thereto and to the extension 104 to move upwardly that end of said lever 170 which is in contact with the toe 168 of the pawl 164. The end 174 of the lever 170 may rest upon a stop 175 carried by the extension 104, being held

thereagainst by the spring 173. Passing down through the stop 175 and slidably vertically therein is a latch pin 176 suitably connected to the end 174 of the lever 170. The lower end of the latch pin 176 passes through the extension 104 of the support 89 sufficiently to engage a hole or recess 178 in a slide plate 180 in which is suitably fastened the printing element 110 as shown in Figures 5 and 6. The slide 180 is arranged to slide reciprocably toward the left and right of Figure 5 in the recess 182 of the support 89. The slide 180 is formed with a bevel 184 at the upper side of the left hand end thereof. Upon this bevel may bear the lower end of the latch pin 176 when the slide plate is moved toward the left, the latch pin 176 moving upwardly in the stop 175, the lever 170 moving upon its pin 171 against the bias of the spring 173. When the slide has been moved to the extreme left hand position, in which position the printing element 110 becomes positioned beneath the inking mechanism of the printing device 107, the latch 176 may drop into the recess 178 to hold the slide 180 against motion.

At the right hand end of the slide 180 is shown a bracket 186 to which is fastened spring 187, the opposite end of the spring 187 being suitably fastened to a bracket held by the support 89. This spring 187 acts to bias the slide plate 180 to move toward the right. If the latch pin 176 is lifted by tilting the lever 170 upon its pin 171 against the bias of the spring 173 until the lower end of the latch pin 176 is released from the recess 178 of the slide plate 180, then the slide plate 180 carrying the printing element or plate 110 is drawn to the right by the spring 187 until the printing plate 110 is clear of the sheet 5. In this position in the manner referred to above the plate may be changed and a new one substituted therefor.

From the above description and by reference to Figure 5 of the drawings it will be understood that when the handle 112 is depressed to cause printing of the sheet in the manner described, the slide 155 will be lifted from its position of rest upon the pin 158. In this motion the pin or lug 166 acts to lift the pawl 164 by contacting the right hand end thereof, tilting this pawl upon its pin 160 and lifting the toe 168 thereof from the right hand end of the lever 170 until the pin 166 passes above said pawl 164. In this movement no movement of the lever 170 takes place and the slide plate 180 remains in the latched position. When, however, under the action of the spring 130 the handle 112 is permitted to return upwardly, the extension 155 will be moved downwardly and the slide plate 150 will be carried downwardly. The pin 166 which, during the upward movement has passed above the pawl 164 and permitted said pawl to drop back with its toe 168 resting upon the lever 170, will press upon the pawl 164 and cause the toe 168 to press upon the right hand end of the lever 170 thus causing the end 174 of said lever 170 to move upward and to carry the latch pin 176 upwardly to release the slide plate 180 in the manner described above. The arrangement of the parts is such that when the handle 112 approaches the upper limit of its motion the pressure of the pin 166 upon the pawl 164 is transmitted to the latch pin 176 and the motion thereof is completed upon completion of the upward movement of the handle 112. Thus the slide plate 180 carrying the printing element 110 is released for movement of

the printing element to the position clear of the sheet only after the completion of the inking operation effected by movement of the roller toward the right and again toward the left over the printing plate 110.

It will be apparent, from the description just given, that the invention comprises movement of the printing element into and out of a position clear of the sheet and into and out of the printing position by a motion of straight reciprocation, as compared with the angular movement effected by the means shown in Figures 1, 2 and 3. The slide 180 is provided with a suitable extension 188 carrying a knob 189 by means of which the operator, against the bias of the spring 187 after changing the printing element or plate 110, may move the slide plate 180 toward the left into the position of engagement of the latch 176 as described.

The knob 189 may be provided with a shank 190 passing through the extension 188. Said shank 190 below said extension 188 is provided with a collar 192 fastened to said shank somewhat above the lower end thereof. Between the collar and the lower side of the extension 188 is a light spring 193 which biases the shank 190 and the knob 189 to move downwardly with respect to the extension 188. Carried by the knob 189 is a stop pin 195 arranged to pass through a hole 196 in the extension 188 when in register therewith. The shank 190 is rotatable upon its axis in the hole in the extension 188 through which it passes. The stop pin 195, therefore, when lifted and turned into a position out of alignment with the hole 196 may rest upon the upper face of the extension 188 to hold the shank 190 in the upward position against the bias of the spring 193. The lower end 191 of said shank may engage with a hole or recess 198 in the support 89 when the knob is rotated for alignment of the stop pin 195 with the hole 196, the spring 193 biasing the shank to move into said recess 198. This arrangement of the knob and shank 190 provides means for preventing movement of the slide plate 180 upon release of said slide plate from engagement with the latch pin 176. This device may be used by the operator to hold the printing element 110 in position for a second impression, that is, a second operation of the handle 112 from the same printing element or plate 110. By a simple turning movement of the knob 189 into or out of the position in which the stop pin 195 may pass downwardly through the hole 196, which motion may be given simultaneously with movement of the slide plate 180 toward the left in Figure 5, the end 191 of the shank 190 may be in position to engage the hole or recess 198 upon completion of the movement of the slide plate 180 toward the left. It will thus be clear that when feeding motion of the sheet 5 is effected in the manner described in connection with Figures 1 and 2 the sheet may be stopped in its proper position for receiving an imprint from the printing element 110 and that this imprint may be repeated upon the succeeding form area of the sheet or in any second position determined by the form of the cam 44 and the notches 46 thereof with respect to the movement effected by the rotation of the roll 11. Two impressions from the same plate may be made on two succeeding form areas if a cam of the type shown in Figure 4 is used in connection with a gear reduction mechanism producing one revolution of the cam for a delivery of the sheet

corresponding to one form area, or two impressions from the same plate per form area may be obtained if a cam of the type shown in Figures 7 or 8 is used.

In Figure 5 is shown the bell crank 50, the arms 52 and 60 thereof being shown as well as the rod 73 connecting between the arm 60 and the treadle 75. The arrangement of these members, partly shown in dotted outline in Figure 5, is intended to be the same as that shown in Figure 10 2. In addition, however, to the arm 60 is pivotally fastened upon a pin 200 an arm 202. Slidably fitting into said arm 202 is a shank 204 of a latching extension 206. A spring 208 surrounding the shank 204 and between the arm 202 15 and the extension 206 biases said extension 206 to move upwardly away from the arm 202. The extension 206 passes upwardly through a hole in the support 89 into a recess 210 in the bottom face of the slide plate 180. Under the bias of the 20 springs 25 and 65, as shown in Figure 2, the lever 60 keeps the extension 206 in engagement with the recess 210 when the lever 60 is in its upper position, the cam ball 62 being then held in the recess 46. When, however, pressure is placed 25 upon the treadle 75 and the lever 60 is moved downwardly, the arm 202 also is moved downwardly and may draw the extension 206 from the recess 210 in the slide plate 180. To this end the shank 204 may have fastened thereto a pin 207 30 slidably in a slot 205 in the arm 202. When under the bias of the spring 208 the pin 207 bears against the upper end of the slot 205 the extension 206 thereafter will move with the arm 202. The arrangement being described is intended to 35 be alternative to the releasing mechanism, including the latch pin 176, which is connected to be operable with the handle 112 of the printing device 107. It will be understood, after the imprint is made upon the sheet and the treadle 75 40 is pressed to start the sheet to move into the next position of printing, that during this movement of the sheet the printing element 110 may be moved from the printing position into the position clear of the sheet. Withdrawal of the latching extension 206 from the recess 210 will effect 45 this release of the plate 180 without relation to the mechanism for applying the inking material to the sheet, provided said plate is not under pressure of the printing device.

Moreover, when the treadle 75 is released and the cam ball 62 may, therefore, move into the recess 46, thus restoring the arm 60 of the bell crank 50 to its upper position, the latching extension 206 will be moved to bear upon the under face of the slide plate 180 or will be clear of the slide plate 180, depending upon the place at which the arm 202 is attached to the arm 60 and depending upon the relation of the mechanism for effecting movement of the sheet to the printing mechanism. As shown in Figure 5, the left hand end of the slide plate 180 may be provided with a bevel 185 on its lower side similar to the bevel 184 on its upper side so that, as the operator moves the slide plate 180 toward the left, the latching extension 206 may be pushed downwardly against the spring 208 and then may be moved by said spring upwardly into the recess 210 when the slide plate 180 has reached the extreme left hand position ready for printing.

The embodiments of the invention illustrated in the drawings are intended as examples of the application of the invention to printing processes in which a sheet is moved in the direction of a surface dimension thereof a predetermined

amount between two printing positions and especially those applications in which the printing element must be changed for each printing position or is used for only a few impressions, therefore to be replaced by another printing element. The invention provides ready accessibility to the printing element, ready inspection thereof to identify it with the form area of the sheet to be printed and ready identification of the printing element when in the position clear of the sheet for removal thereof from the printing device to the file or storage device in which it is to be kept. Modifications of the arrangement of the parts may be utilized without departing from the spirit of the invention according to which the printing element is moved to the position clear of the sheet in a direction like-extending with a surface dimension of the sheet, generally in a plane parallel to the surface of the sheet. All such variations and modifications are within the scope of the invention.

Having thus described my invention I now claim:

1. Apparatus comprising a printing element, means for applying pressure upon the printing face of said element, means for moving sheet material in the direction of a face dimension thereof and between said printing element and said pressure means, said printing element and said pressure means, said applying means being supported and arranged to be moved together into and out of said relation to said sheet in a direction generally parallel to the face of said sheet in its printing position.

35 2. Apparatus comprising a printing element, means for applying pressure upon the printing face of said element, means for moving sheet material in the direction of a face dimension thereof and between said printing element and said pressure means, and means for removably supporting said printing element in said relation to said pressure means and to said sheet, said supporting means and said pressure means together being reciprocal into and out of the position of said relation of said printing element and said pressure means to said sheet in a direction generally parallel to said face of the sheet.

3. Apparatus comprising means for making a mark upon the surface of a sheet, means for moving said sheet from the position in which it is so marked a predetermined distance in a direction generally like-extending with a surface dimension of the sheet to a second position for marking another portion of the sheet, and means for holding said moving means against movement upon completion of said movement through said predetermined distance, said means for marking the sheet being constructed and arranged for movement thereof in a direction like-extending with a surface dimension of the sheet to a position clear of the sheet in which said marking means is accessible for replacement by another marking means and being so movable upon release of said sheet moving means from said holding means.

65 4. Apparatus comprising means engaging a sheet to move said sheet in the direction of a surface dimension thereof upon movement of said engaging means, power means, means for causing said power means to move said sheet engaging means, means acting to maintain the movement of said sheet engaging means under the action of said power means during the movement of the sheet through a predetermined distance in said direction of its movement, means for releasing said sheet engaging means from the action of

said power means upon completion of said movement of the sheet through said predetermined distance, means for making a mark on the surface of said sheet arranged to make such mark in a predetermined relation to the sheet upon completion of said predetermined movement, and means operable upon completion of the marking operation and upon action of said means for maintaining movement of the sheet to cause movement of said marking means in a direction like-extending with a surface dimension of the sheet to a position clear of the sheet in which position said marking means is accessible for replacement by another marking means.

5. Apparatus comprising rotary means contacting a sheet to move said sheet in the direction of a surface dimension thereof upon rotation of said rotary means, power means, means operable to connect said power means to said rotary means to cause rotation of said rotary means, said connecting means also being operable to disconnect said power means from said rotary means, means for holding said rotary means against movement upon disconnection of said power means therefrom, means operable at will to release said holding means and to operate said means for connecting said power means to said rotary means to cause rotation of said rotary means, means for limiting the motion of said rotary means to cause a predetermined movement of the sheet, said holding means being so constructed and arranged with respect to said means connecting said power means to said rotary means as to cause disconnection of said power means from said rotary means upon completion of said predetermined movement of the sheet to interrupt movement thereof and thereafter to hold said rotary means and said sheet against movement until released, a printing element supported adjacent said surface of the sheet arranged to be movable in a direction like-extending with a surface dimension of the sheet to a position clear of the sheet in which said printing element is accessible for replacement by another printing element, and means for so moving said printing element upon release of said means holding said rotary means.

6. Apparatus comprising rotary means contacting a sheet to move said sheet in the direction of a surface dimension thereof upon rotation of said rotary means, power means, means operable to connect said power means to said rotary means to cause rotation of said rotary means, said connecting means also being operable to disconnect said power means from said rotary means, means for holding said rotary means against movement upon disconnection of said power means therefrom, means operable at will to release said holding means and to operate said means for connecting said power means to said rotary means to cause rotation of said rotary means, means for limiting the motion of said rotary means to cause a predetermined movement of the sheet, said holding means being so constructed and arranged with respect to said means connecting said power means to said rotary means as to cause disconnection of said power means from said rotary means upon completion of said predetermined movement of the sheet to interrupt movement thereof and thereafter to hold said rotary means and said sheet against movement until released, means for actuating said holding means to release said rotary means and to cause connection thereof with said power means, and a printing element supported adjacent the surface of the sheet and arranged upon actuation of said holding means

releasing said rotary means to be movable in a direction like-extending with a surface dimension of the sheet into a position clear of the sheet in which said printing element is accessible for replacement by another printing element.

7. Apparatus comprising means supporting a sheet with at least a portion of its extent in the plane of a surface dimension thereof, means for making a mark upon said surface of the sheet, said marking means including a marking element, said marking element being so supported and arranged adjacent the surface of the sheet as to be biased to move in a direction generally like-extending with a dimension of said surface of the sheet to a position clear of the sheet in which said marking element is accessible, and means connected to a movable member of said means for making a mark upon the sheet and arranged to hold said element against its bias in the marking position during the marking operation of said marking means and to release said marking element upon completion of said marking operation.

8. Apparatus according to claim 7 in which said marking element may be moved at will against its bias from said position clear of the sheet to the position of marking the sheet.

9. Apparatus according to claim 7 in which said marking element may be moved at will against its bias from said position clear of the sheet to the position of marking the sheet, said holding means being arranged to be biased to engage and hold said marking element upon completion of said motion thereof into said marking position.

10. Apparatus comprising means supporting a sheet with at least a portion of its extent in the plane of a surface dimension thereof, means for making a mark upon said surface of the sheet, said marking means including a marking element, said marking element being so supported and arranged adjacent the surface of the sheet as to be biased to move in a direction generally like-extending with a dimension of said surface of the sheet to a position clear of the sheet in which said marking element is accessible, means connected to a movable member of said means for making a mark upon the sheet and arranged to hold said element against its bias in the marking position but capable of movement to release said marking element to move under its bias, and means constructed and arranged to prevent movement of said holding means during part of the motion of said movable member but before completion of the motion of said member completing the marking operation to cause motion of said holding means so as to effect release of said marking element.

11. In combination with a printing device of the type in which the printing element is held in position adjacent one face of the sheet and the inking material is applied to the opposite face of the sheet by means acting to apply pressure to

said opposite face of the sheet to press said sheet against said printing element, means engaging said printing element and biased to hold said element against motion thereof when said element is in printing position, said element when released from said engagement being movable in a direction generally like-extending with a surface dimension of the sheet to a position clear of the sheet, means engaged by a movable member of said pressure applying means during at least a part of the motion of applying pressure upon the sheet but free of force transmitting connection to said biased holding means, said means engaged by said movable member being so constructed and arranged as to receive engagement of said movable member during a part of the motion of said pressure means during which pressure substantially is removed from said sheet and so as to move said holding means against its bias to release said printing element when said force is received from said movable member by said means engaged thereby.

12. Apparatus comprising means for moving a sheet in the direction of a surface dimension thereof, means for intermittently positively holding said sheet moving means against said movement thereof, a printing element arranged adjacent a face of said sheet and to be movable in the direction of a surface dimension of the sheet, means for holding said printing element against said motion, and means connecting said two holding means to release said printing element when said means for holding said sheet moving means is ineffective to hold said sheet against said motion thereof.

13. Apparatus comprising means continuously and positively engaging a sheet to move said sheet in the direction of a surface dimension thereof upon movement of said engaging means, power means, means connected between said power means and said sheet engaging means to cause said power means to move said sheet engaging means and alternately to release said sheet engaging means from said power means while preventing movement of said sheet engaging means, a printing element arranged adjacent a face of said sheet and to be movable in the direction of a surface dimension of the sheet, means for holding said printing element against said motion, and means connecting said holding means with said means connected between said power means and said sheet engaging means and arranged to release said printing element upon action of said means connected between said power means and said sheet engaging means which causes said power means to move said sheet engaging means.

14. Apparatus according to claim 7, including means operable at will to prevent movement of said element under its bias when released by said holding means.

HENRY VAN RIPER SCHEEL.
